(No Model.)

E. G. MEAD.
SKETCHING EASEL.

No. 337,512.

Patented Mar. 9, 1886.

UNITED STATES PATENT OFFICE.

EDWARD G. MEAD, OF BOSTON, MASSACHUSETTS, ASSIGNOR TO THE PRANG EDUCATIONAL COMPANY, OF SAME PLACE.

SKETCHING-EASEL.

SPECIFICATION forming part of Letters Patent No. 337,512, dated March 9, 1886.

Application filed September 26, 1885. Serial No. 178,276. (No model.)

To all whom it may concern:

Be it known that I, EDWARD G. MEAD, a citizen of the United States, residing at Boston, in the county of Suffolk and State of Massachusetts, have invented certain new and useful Improvements in Sketching - Easels, of which the following is a specification.

My invention is an artist's easel consisting of a head-piece and three adjustable legs secured thereto, a canvas-holder, and an adjustable rest, all constructed and arranged as fully set forth hereinafter.

In the drawings, Figure 1 is a perspective view of my improved easel as set up for use. Fig. 2 is a perspective view of the same as folded for transportation without the rest. Fig. 3 is a longitudinal section on the line 1 2, Fig. 2. Fig. 4 is a rear view. Fig. 5 is a side view of Fig. 1, showing the holder in a different position. Fig. 6 is an end view of the rest. Fig. 7 is a transverse section of the rest. Fig. 8 is a plan of the rest.

The easel consists, essentially, of a head-piece, A, two legs, B B, pivoted to the head-piece to swing laterally, a leg, C, pivoted to the head-piece to swing forward and back, a rest, D, which may be clamped to the legs B B, and a canvas-holder, E.

The head-piece A has side slots, a, receiving tongues b at the upper ends of the legs B, pins b, extending through the head-piece and through the tongues and pivoting the legs to the head-piece. At the rear the head-piece is cut away to form two side lugs, c c, through which and through the upper end of the leg C passes transversely a pin, e, upon which the rear leg swings. By thus pivoting the legs to the head piece the rear leg may be swung forward, and the side legs may be swung inward until they are parallel with each other, and with the rear leg, C, between them, all being upon the same plane with each other and with the head-piece A.

Each leg consists of two sections, d d', the upper section, d, being pivoted to the head-piece, and the lower section, d', sliding upon the upper section, and being provided at the lower end with a pointed pin, f, for preventing the leg from slipping upon its support.

The upper and lower sections of the legs may

slide upon each other, being held together by the ordinary guiding-bands g g', and secured in proper position by set-screws h after adjustment.

When the easel is to be contracted for storage, the lower ends, d', of the legs are slid upward as far as they will go, and the parts are all brought to the position shown in Fig. 2. When the parts are thus arranged, they may be held in place by means of a rod or bar, i, which extends through a longitudinal slot, x, in the head-piece A, and also in a slot, y, formed by coinciding grooves in the contiguous faces of the parts d d' of the central or rear leg, C, as shown in Fig. 4, the vibration of the leg C being prevented until the bar i is withdrawn from its place. A set-screw, j, passing transversely through the head-piece A, may be brought to bear upon the bar i, so as to hold it in place, if desired.

The rest D is made in two pieces, m m', the latter having a longitudinal slot, n, and the former being provided with a longitudinal rib, s, adapted to fit the slot n, and thereby permitting the pieces to be carried to and from each other in securing the rest upon the legs B B, and at the same time preventing one piece from swinging out of line with the other.

Different means may be employed for drawing the pieces together and clamping them to the legs; but I prefer to use a screw-rod, r, extending from the piece m' through a hole in the piece m, and provided at the outer end with a thumb-nut, t. By turning the nut to the left the pieces may be slightly separated, so as to permit their adjustment to any desired position upon the legs B B, and after the adjustment a slight turn of the nut, to the right will clamp the parts firmly against the legs, so as to support the heaviest canvas.

When the rest is to be removed, the parts are so far separated as to permit their withdrawal from the legs.

The canvas-holder consists, essentially, of a rod having one end bent at an angle thereto, and provided with a flat head or button, which may be brought in front of the upper part of the canvas to hold it securely upon the rest. The holder may consist of the rod

i, which, as before described, is used to hold the parts of the easel together when folded for storage, and the bent end of such a rod may be provided with a button, *k*. The holder is fitted to a hole in the head of the easel, and it may be inserted in such a manner as to have the button extend below the head, as shown in Fig. 1, so as to secure a small canvas upon the easel, or it may be inserted so that the button projects above the head of the easel, as shown in Fig. 5, in which case a very large canvas may be held. It will be seen that the holder may thus be adjusted in the desired position to hold any sized canvas, and, if desired, it may be secured in position after adjustment by a thumb-screw, *j*.

From the above it will be seen that the improved easel is capable of extended use, while at the same time it is compact and strong, and the rest may be adjusted in any desired position, not being limited to any definite points of adjustment, as is usual, and by means of the adjustable holder many and various sized canvases or other articles may be securely held in the desired position.

It is evident that the rest and holder may be used independent of each other, and one or both may be used in connection with easels of different construction from that described and shown.

What I claim is—

1. The combination, with the head piece *A*, having a longitudinal slot, of the side legs, *B* *B*, and rear leg, *C*, each made of two parts sliding upon each other, and a bar or rod, *i*,

passing through the slot and extending between the parts of the rear leg, to hold the same in position when folded for storage, substantially as described.

2. A canvas-rest for an easel, consisting of two sections, *m* *m'*, one being provided with a recess, and the other with a rib extending into said recess, and a clamping-screw passing through both sections, whereby the rest may be secured to the legs of an easel at any desired position, substantially as described.

3. The combination, with the head-piece of an easel having a longitudinal slot, as *x*, of a canvas-holder consisting of a bar or rod, *i*, having a button, *k*, upon its bent end, and adapted to be secured in the slot of the easel-head, so that the button will bear upon the upper part of any sized canvas and hold it in position, substantially as described.

4. The combination, with an easel, of a rest consisting of two sections arranged to be secured to the legs of the easel in any desired position, and a canvas-holder consisting of a rod having a button upon its end arranged to be secured in the head of the easel and bear upon the upper part of the canvas, substantially as described.

In testimony whereof I have signed my name to this specification in the presence of two subscribing witnesses.

EDWARD G. MEAD.

Witnesses:

MICHAEL MAGINNIS,
WM. WARREN TOWLE.
